METHOD FOR MOISTENING TOBACCO

Rush D. Touton, Cynwyd, Pa., assignor to Wurton
Machine Company, Philadelphia, Pa., a cor-
poration of Pennsylvania

Application December 23, 1938, Serial No. 247,332

7 Claims. (Cl. 131—140)

This invention relates to a method for moistening tobacco and other packed materials.

While this invention will be adaptable for the moistening of any tobacco, it will be especially advantageous for the moistening of tobacco such as filler, binder and wrapper tobacco used in the manufacture of cigars; and will be especially characterized by the fact that the moistening will be effected with the tobacco in baled form.

10 As is well known, tobacco is ordinarily packed for shipment in bales, hogsheads, or the like, in which the tobacco leaves are relatively tightly packed together. Thus, for example, tobacco used in the manufacture of cigars is made up into 15 hands comprising a plurality of leaves secured at their butts. A plurality of hands are in turn baled or compressed, usually in two rows with the tips of the leaves adjacent and the butts outward, into a case or box in which the tobacco dries out 20 to a state of relative brittleness.

For preparation of such tobacco for fermentation or manufacture into cigars the hands must be separated and the leaves moistened to enable their manipulation without breaking.

25 Heretofore the separation of the hands forming a bale or case of tobacco without excessive breakage has presented a problem, since the leaves forming the hands are dry and brittle and the hands are more or less adhered together from the 30 pressure used in baling them and their subsequent drying out.

Various attempts have been made to moisten the tobacco in the baled form in order to facilitate the separation of the hands, but none have proved 35 entirely successful, variously for the reasons that excessive time is required, excessive or non-uniform wetting occurs, and dipping in water or treatment with steam vapor at atmospheric pressure causes damage to delicate tobaccos.

40 Now in accordance with this invention a method is provided whereby tobacco in baled form may be readily and quickly moistened to enable the hands to be separated without breakage and further whereby, if desired, the leaves 45 forming the hands may be substantially uniformly moistened and otherwise treated to the extent desired for fermentation or manufacture of the tobacco.

Generally speaking the method in accordance 50 with this invention comprises subjecting tobacco in bale form, after removal of the box or casing, to a vacuum, then flooding the bale with liquid, as water, and then draining off the liquid. From the more specific standpoint the method will comprise subjecting the baled tobacco to vacuum

during and/or after draining off of the liquid and variously at the same time to heat. In the different stages of the process the degree of vacuum and/or the temperature may be varied, depending upon the type of tobacco or the result to be 5 obtained.

The characteristics of the method from a more detailed standpoint will, it is believed, be made apparent from the following description of apparatus for the carrying out of the method.

Having now indicated, in a general way, the 10 nature and purpose of this invention, I will proceed to a detailed description of apparatus adaptable for use in the carrying out of the method, all with reference to the accompanying drawing, in 15 which:

Figure 1 is a diagrammatic view of a form of apparatus adapted for use in carrying out the method according to this invention.

Figure 2 is a sectional view through the treat- 20 ing chamber included in the apparatus shown in Figure 1.

In the several figures A is a chamber provided with a coil R for heating or cooling fluid and dimensioned to hold a bale or case or a plurality of 25 bales or cases of tobacco. The chamber A may, for example, be adapted to contain six cases of tobacco of a standard size, (i. e., 29"x29"x4").

The opposite ends of the chamber A are equipped with tight fitting and gasketed doors 30 B, B adapted to be held closed by means of dogs C.

A conveyor D, which may be endless, is arranged for the delivery of tobacco to the chamber A from any suitable point and the conveyor D' will serve to transfer the tobacco to any desired 35 point after completion of the treatment. The conveyors D and D' may be driven by any suitable power. A conveyor D'' may be installed within the chamber.

A vacuum pump E will be connected to the top 40 of chamber A through a conduit P provided with a valve F and a pressure gauge G will be connected to the chamber to indicate the pressure (vacuum) therein. The chamber A will also be provided with a valved vent Q under control of an 45 adjustable vacuum responsive device Q' and with a water level glass V. A thermal indicating and control device S will operate to indicate the temperature within the chamber A and to actuate a regulating and control valve Y for control of heat- 50 ing and cooling fluid to coil R.

Below the bottom of the chamber A and connected with the bottom thereof by a conduit K provided with a valve L is a tank H adapted to contain a liquid, as water, and having a capacity 55

- 5 of at least that of chamber A. A float valve Z
5 prevents the entry of water into conduit P. Within
in the tank H is a heating element I, which may
be an electrical element or a coil connected with
5 a suitable source of heated fluid as, for example,
steam.

10 The tank H is connected with a water supply
by means of a valved pipe J and is provided with
a vent M. A two-way pump N is connected to the
10 tank H and to conduit K, by conduits U, controlled
by a valve U'.

15 A thermal indicating and control device T will
operate to indicate the temperature of the liquid
in tank H and to actuate a regulating and control
15 valve C for control of the heating element I.

20 Stops A' are provided in chamber A at a height
to overlie the containers O for the tobacco and
prevent the bales from floating when liquid is in-
20 troduced into the chamber.

25 20 In proceeding for the carrying out of the
method in accordance with this invention, with
use of the apparatus above described, the wooden
case or box is removed from several bales of to-
bacco X, they are placed in open metal baskets
25 or perforated containers O, provided with fol-
lowers O' to accommodate the containers to bales
of various lengths, and so supported are entered
into the chamber A and rest on the conveyor D''.
The doors B of chamber A are dogged shut and
30 the vacuum pump E is operated to draw a vacuum
in the interior of the chamber A, the valve L in
water conduit K, the valve U' in conduit U and
the vent Q being closed. The vacuum responsive
30 control Q' for valve Q is set for maintenance of
35 the desired vacuum.

35 The vacuum drawn on the chamber A may be
a low vacuum, say within the range 1-28 inches
of mercury, the particular vacuum depending upon
whether or not the vacuum pump is continued
40 in operation during flooding of the chamber. Desirably the vacuum maintenance will be such that
the temperature of the liquid will be below the
boiling point corresponding to the absolute pres-
sure.

45 40 A vacuum of a degree sufficient to effect flood-
ing of chamber A from tank H having been drawn
on chamber A, the valve F in conduit P will be
closed and the valve L in conduit K will be opened.
On the opening of valve L water from the tank
50 H will rush into chamber A and flood the chamber
and the bales of tobacco therein. The water will
desirably be at a temperature of say about 75° F.
or within the range 60-110° F.

55 50 The bales of tobacco in chamber A having been
flooded with water and sufficient time having
been allowed to permit the water to penetrate
throughout the bales, the interiors of which are,
of course, under low pressure, the vent Q is
opened and the water rapidly drained back into
60 tank H.

65 The water having been drained out of chamber A, the doors may be opened and the wetted
bales discharged from the chamber onto the
conveyor D' and further bales are introduced
into the chamber from conveyor D for treatment
as described.

70 In certain cases the valve F in conduit P may be
left open and the vacuum pump continued in
operation during the admission of water to
chamber A, with regulation of the vacuum at the
desired point by regulator Q', and again after
the water is drained from chamber A the water
valve L may be closed and the bales of tobacco
again subjected to reduced pressure for a period
75 say from .5-1.5 hours to allow free water in the

5 bales to be absorbed by the tobacco leaves. When
the bales are subjected to vacuum after drain-
ing off of the water from chamber A, a heating
fluid, as steam, may be introduced into the coils
R and the temperature within the chamber raised
5 to say 80-90° F. to facilitate the removal of ex-
cess water from the tobacco by vaporization.
Under certain conditions, the temperature of the
chamber will be raised above the boiling point of
water corresponding to the absolute pressure 10
10 maintained in the chamber.

15 In many cases the operation will be facilitated
by use of the two-way pump N for flooding and
draining of the chamber A and variously vacuum
may be desirably maintained on the chamber 15
during the flooding of the chamber and also dur-
ing the draining off of the water therefrom by
the pump N, thus carrying out the entire treat-
ment under reduced pressure.

20 Thus, by way of more specific example of pro-
cedure using the two-way pump N, the chamber
containing the tobacco is put under vacuum, say,
for example, a vacuum of 20'' of mercury, by
operation of the vacuum pump E. The valve L
is left closed, the valve U' opened and the pump 25
N operated to flood the chamber with water, the
vacuum being maintained by continued opera-
tion of the pump E and the regulator Q'. The
pump N is then reversed and the water with-
drawn from the chamber while continuing the 30
maintenance of a vacuum. Such procedure will
have the effect of lessening the liquid pressure
on the tobacco in chamber A to a greater degree
than in those cases where the water is drained
35 from chamber A by admitting air to chamber A
through vent Q and will permit treatment of
more delicate types of tobacco with avoidance
of injury.

40 Variously, the vacuum may be changed during
the treatment of the tobacco. For example, a 40
vacuum of 15'' of mercury may be initially drawn
on the chamber containing the baled tobacco,
then during the flooding of the chamber with
liquid a higher vacuum may be drawn, say a
45 vacuum of 20'' of mercury. Finally, during the
draining and for a period thereafter a still
higher vacuum, say a vacuum of 25'' of mercury,
may be drawn.

50 In many instances agitation of the water in
the chamber will be advantageous. Agitation 50
may be effected by so operating the pump N as
to cause the level of the liquid in the chamber
to be raised and lowered.

55 Variously, with various types of tobacco, it
will be desirable to subject the tobacco to liquid
at a different temperature from that of the to-
bacco. Thus, for example, with those tobaccos
most easily susceptible to damage from water,
it will be desirable to have the temperature of
the liquid lower than that of the tobacco, for
example, 10° F. lower than the temperature of
the tobacco.

60 65 In certain cases it will be advantageous to sub-
ject the tobacco to flooding with a liquid so com-
posed as to have a greater or a lesser surface ten-
sion than pure water under the conditions of
pressure and temperature obtaining within the
chamber. By way of example, a liquid which
70 may be advantageously used and which will have
a greater surface tension than pure water may
comprise water containing a mineral salt, as
potassium nitrate, in various amount up to sat-
uration. On the other hand, an advantageous
liquid having less surface tension than pure water
75

may comprise one part of glycerine and four parts of water.

If desired, a flavoring for the tobacco, such as 5 licorice, rum, maple sugar, or the like, a fermentation catalyst or accelerator, such as yeast, enzymes, or the like, may be placed in the water in tank H for transfer to the tobacco when flooded with the water.

It will be understood that it is not contemplated 10 that this invention shall be limited by the detailed description given above for illustrative purposes, since it will be obvious that various modification and in the carrying out of the method may be made without departing 15 from the scope of this invention.

What I claim and desire to protect by Letters Patent is:

1. The method of moistening baled tobacco which includes positioning a bale of tobacco in a 20 chamber, reducing the pressure within the chamber below atmospheric pressure but not below the vapor pressure of the liquid to be introduced into the chamber at the temperature obtaining, flooding the entire bale of tobacco by introducing 25 a liquid into the chamber, rapidly draining off the liquid from the chamber, reducing the pressure within the chamber after the liquid has been drained off therefrom to a pressure below the vapor pressure of the liquid at the temperature 30 obtaining and permitting the tobacco to remain in the chamber under such pressure for a period to permit removal of excess liquid from the tobacco by vaporization.

2. The method for moistening baled tobacco 35 which includes positioning a bale of tobacco in a chamber, reducing the pressure within the chamber below atmospheric pressure but not below the vapor pressure of the liquid to be introduced into the chamber at the temperature obtaining, flooding the entire bale of tobacco by introducing 40 a liquid into the chamber, rapidly draining off the liquid from the chamber, raising the temperature within the chamber after the liquid has been drained off therefrom to a temperature above the boiling point of the liquid at the pressure obtaining and permitting the tobacco to remain in the chamber at such temperature and under such pressure for a period to permit removal of excess liquid from the tobacco by 45 vaporization.

3. The method for moistening baled tobacco which includes positioning a bale of tobacco in a 50 chamber, reducing the pressure within the chamber below atmospheric pressure but not below the vapor pressure of the liquid to be introduced into the chamber at the temperature obtaining, flooding the entire bale of tobacco by introducing 55 a liquid into the chamber, said liquid when introduced being at a temperature lower than that of the tobacco, rapidly draining off the liquid from the chamber, reducing the pressure within the chamber after the liquid has been drained off therefrom to a pressure below the vapor pressure of the liquid at the temperature obtaining and permitting the tobacco to remain in the chamber under such pressure for a period to permit removal of excess liquid from the tobacco by vaporization.

4. The method for moistening baled tobacco

which includes positioning a bale of tobacco in a chamber, reducing the pressure within the chamber below atmospheric pressure but not below the vapor pressure of the liquid to be introduced into the chamber at the temperature obtaining, flooding the entire bale of tobacco by introducing a liquid into the chamber, said liquid when introduced being at a temperature lower than that of the tobacco, rapidly draining off the liquid from the chamber, raising the temperature within the chamber after the liquid has been drained off therefrom to a temperature above the boiling point of the liquid at the pressure obtaining and permitting the tobacco to remain in the chamber at such temperature and under such pressure for a period to permit removal of excess liquid from the tobacco by vaporization.

5. The method for moistening baled tobacco which includes positioning a bale of tobacco in a chamber, reducing the pressure within the chamber, flooding the chamber with a liquid in an amount sufficient to completely immerse the tobacco while maintaining a reduced pressure within the chamber, rapidly draining off the liquid from the chamber to a point out of contact with the tobacco, further reducing the pressure within the chamber after the liquid has been drained off, and permitting the tobacco to remain in the chamber under such reduced pressure for a period sufficient to permit absorption by the tobacco of a substantial amount of the unabsorbed liquid retained in the bale.

6. The method for moistening baled tobacco which includes positioning a bale of tobacco in a chamber, reducing the pressure within the chamber, flooding the chamber with a liquid in an amount sufficient to completely immerse the tobacco while maintaining a reduced pressure within the chamber, rapidly draining off the liquid from the chamber to a point out of contact with the tobacco, further reducing the pressure within the chamber after the liquid has been drained off, permitting the tobacco to remain in the chamber under such reduced pressure for a period sufficient to permit absorption by the tobacco of a substantial amount of the unabsorbed liquid retained in the bale, and then raising the temperature within the chamber to evaporate the remainder of the unabsorbed liquid.

7. The method for moistening baled tobacco which includes positioning a bale of tobacco in a chamber, reducing the pressure within the chamber by about 15 inches of mercury, flooding the chamber with a liquid in an amount sufficient to completely immerse the tobacco while maintaining a reduced pressure equivalent to a vacuum of approximately 20 inches of mercury within the chamber, rapidly draining off the liquid from the chamber to a point out of contact with the tobacco, further reducing the pressure within the chamber after the liquid has been drained off to a pressure equivalent to a vacuum of approximately 25 inches of mercury, and permitting the tobacco to remain in the chamber under such reduced pressure for a period sufficient to permit absorption by the tobacco of a substantial amount of the unabsorbed liquid retained in the bale.

RUSH D. TOUTON.
